UNITED STATES PATENT OFFICE.

LAWRENCE L. URBAN, OF ROWSON, OHIO.

CURTAIN-POLE FASTENER.

1,411,139.

Specification of Letters Patent. Patented Mar. 28, 1922.

Application filed July 22, 1919. Serial No. 312,642.

To all whom it may concern:

Be it known that I, LAWRENCE L. URBAN, a citizen of the United States, residing at Rowson, in the county of Hancock and State 5 of Ohio, have invented certain new and useful Improvements in Curtain-Pole Fasteners; and I do hereby declare the following to be a full, clear, and exact description of the invention, such as will enable others 10 skilled in the art to which it appertains to make and use the same.

This invention relates to window shade and curtain pole supports, and the primary object of the invention is to provide an improved combined window shade and curtain pole holder in which the shade brackets and curtain pole holders are adjustable in a horizontal and vertical plane respectively, so that curtain shades of various widths 20 can be accommodated and the curtain pole supported at the desired height.

A further object of the invention is to provide an improved combined window shade and curtain pole holder in which the 25 curtain pole holder can be adjusted the desired distance above the curtain shade brackets.

A still further object is to provide an improved combined window shade and curtain 30 pole support, which is durable and efficient in use, one that is simple and easy to manufacture, and one that can be placed upon the market at a reasonable cost.

With these and other objects in view, the 35 invention consists in the novel construction, arrangement and formation of parts, as will be hereinafter more specifically described, claimed and illustrated in the accompanying drawings forming a part thereof, in 40 which:

Figure 1 is a fragmentary front elevation of a window frame showing the improved curtain pole and window shade support secured thereto in operative position.

45 Figure 2 is a side elevation of one of the improved curtain pole and window shade bracket supports removed from the window frame.

Figure 3 is a detail cross section taken 50 on the line 3—3 of Figure 2.

Figure 4 is a detail cross section taken on the line 4—4 of Figure 2.

Referring to the drawings in detail, wherein similar reference characters designate 55 corresponding parts throughout the

several views, the numerals 1 and 2 generally indicate the improved window shade and curtain pole supports which are adapted to be secured to the opposite sides of a window frame, as clearly shown in Figure 1 of 60 the drawings. Each of the window shade and curtain pole supports are identical in construction and each include the body plate 3 having the upwardly and inwardly extending arms 4 and 5, which are positioned 65 at right angles to each other. The base 3 has a plurality of openings 6 formed therein for the reception of suitable fastening elements whereby the members 1 and 2 may be readily secured in position on a window 70 frame. The arms 4 and 5 have their longitudinal edges curved and bent inwardly as at 7 to form guide flanges 8, for the reception of the shade brackets 9 and the curtain pole supporting members 10. The window 75 shade brackets 9 include the base portion 11 and the outwardly extending arms 12 constructed in the usual manner for the reception of the terminals of the curtain shade roller. The upper and lower edges of the 80 plate are crimped, as at 13, for a purpose which will hereinafter more fully appear. The plate 11 is mounted upon an inner plate 14 which has its upper and lower edges received in the flanges 8 and the plate 11 and 85 the plate 14 are adjustably connected together by means of a nut and bolt 15. Upon adjustment of the thumb nut, the plate 11 and plate 14 may be brought forcibly into engagement with the flanges and thus held 90 in adjusted position. The corrugated edges of the plate 11 prevent slipping of the shade brackets. The curtain pole supporting members are also adapted to be mounted on the arms 4 and include an outer plate 16 95 and an inner plate 17, which is slidably received in the flanges 8 formed on the edges of the arms 4 and the inner plate 17 carries an outwardly extending bolt 18 which extends through an opening in the outer plate 100 15. A suitable thumb nut 19 is threaded on the bolt so that the same can be adjusted to firmly clamp the plate in engagement with the flanges 8 so as to prevent movement of the plate on the flanges. The 105 outer plate 16 has its side edges crimped so as to provide a plurality of teeth for engaging the flanges, so that a firm grip may be obtained thereon. The outer end of the bolt 18 is provided with a hooked end 20 110

- for the reception of the terminals of the curtain rod. Thus it can be seen that by loosening the thumb nut 19, the curtain pole supporting member 10 can be adjusted 5 towards or away from the shade bracket, as may be desired. The terminals of the arms 4 and 5 are also provided with a plurality of openings 21 for the reception of suitable fastening elements and when a curtain 10 is to be used which is wider than the window frame, the arms 5 are adjusted outward and away from the window frame until the base portion 3 extends beyond the same and then the fastening elements are driven into the 15 window frame through the openings 21.

16 The shade brackets 11 and the curtain pole supporting members 10 can be mounted in either arm desired, so that either of the arms may be secured to the window frame which 20 is found most desirable.

17 From the foregoing description it can be seen that an improved curtain shade and curtain pole supporting device is formed in which the shade brackets can be adjusted 25 towards or away from each other according to the width of the shade and in which the curtain pole supports can be adjusted towards or away from the shade brackets so that the curtain pole can be supported at 30 the desired height above the shade brackets.

18 In practice, I have found that the form of my invention illustrated in the accompanying drawings and referred to in the above description, as the preferred embodiment,

is the most efficient and practical; yet realizing the conditions concurrent with the adoption of my device will necessarily vary, I desire to emphasize that various minor changes in details of construction, proportion and arrangement of parts may be resorted to, when required without sacrificing any of the advantages of my invention as set forth. 35

40 What I claim as new is:

1. A device of the class described having a support, a plate in engagement therewith, a screw shank extending from and turnably mounted in the plate, fastening means to secure the plate to the support including a nut movable on the screw shank and a supporting means in extension of the screw shank. 45

2. A device of the class described having a support with flanges providing a channel, a plate movable in the channel, a plate disposed against the flanges, a screw shank passing through the second plate and mounted on the first plate, a nut on the shank engageable against the second plate, and a supporting member extending from the 50 shank. 55

55 In testimony whereof I affix my signature in presence of two witnesses.

LAWRENCE L. URBAN.
